UNITED STATES PATENT OFFICE.

WILLIAM R. RYAN, OF CHICAGO, ILLINOIS.

SWITCH-TARGET.

1,178,265.

Specification of Letters Patent.

Patented Apr. 4, 1916.

Application filed June 25, 1915. Serial No. 36,263.

To all whom it may concern:

Be it known that I, WILLIAM R. RYAN, a citizen of the United States, and a resident of the city of Chicago, county of Cook, and 5 State of Illinois, have invented certain new and useful Improvements in Switch - Targets, of which the following is a specification.

My invention relates to switch targets 10 such as are used particularly in railway switch yards.

Injury frequently results to switchmen or brakemen engaged about switch yards by reason of the fact that the signal blades 15 and lamps of the switch targets in use at the present time project upwardly from the switch post to such a height as to be in the way of switchmen or brakemen hanging on the sides of moving freight trains.

It is the object of this invention to provide an attachment for switch posts adapted 20 to accommodate the signal blades and lantern of a switch target, in which the signal lamp will be arranged so as to be readily observable but at the same time positioned close to the upper end of the post and therefore out of the way of the switchmen and brakemen riding on passing freight trains.

A further object is the production of a 25 device as mentioned which will be of durable and economical construction and efficient in use.

The invention consists in the combination and arrangement of parts hereinafter 30 described and claimed.

The invention will be best understood by reference to the accompanying drawing, forming a part of this specification, and in which,

Figure 1 is a perspective view of a switch post attachment embodying the invention, and Fig. 2 is a side elevation of the device showing the same applied for use, the lower end portion of the device being broken away 45 to expose the spindle of the switch post.

The preferred form of construction as illustrated in the drawing comprises a socket forming member consisting of a circular base member 1 which is adapted, when 50 in use, to rest upon the upper end of the switch post 2 in connection with which the device is employed. The member 1 is formed with a centrally positioned socket 3 square in cross section adapted to receive the upper 55 end of the rotatably mounted spindle 4 of the switch post, said spindle, as is known,

being adapted for rotation in the setting of the target, the same being locked in adjusted position by means of lever 5 as is readily understood by those skilled in the art. 60

Formed integral with and projecting outwardly and upwardly from the base member 1 are four equally spaced arms 6 rigidly connected at their upper ends by an integral annulus 7. The arms 6 and annulus 7 constitute the lateral walls of an upwardly opening socket which is adapted for the reception of the base portion of the signal lamp 8 in connection with which the device is employed. The arms 6 also serve as a 65 means of support for the two sets of switch blades 9 and 9' which are rigidly secured to said arms by means of bolts and coöperating nuts 10. Said arms 6 are so disposed and spaced that the signal blades will be positioned at right angles to each other as is of course necessary in the employment of the 70 same for signaling purposes.

With the arrangement set forth it will be seen that an exceedingly compact arrangement is produced or one where no space is wasted vertically, the base of the lamp being positioned in the same horizontal plane with the signal blades. This being so the switch target is reduced to a minimum 80 height and thus the possibility of injury to the switchmen and brakemen as above referred to correspondingly reduced. Furthermore the construction set forth is extremely simple and economical and hence 85 may be manufactured at a low cost, and is adapted for efficient service as a switch target.

While I have illustrated and described the preferred form of construction for carrying my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention what I claim as new and desire to secure by Letters Patent is:

1. In a switch target, the combination with the rotary spindle of a switch post, of a socket operatively connected with the upper end of said spindle adapted to receive 110 the base portion of a signal lamp; and signal blades connected with and radiating

from the sides of said socket, substantially as described.

2. In a switch target, the combination with the rotary spindle of a switch post, of 5 a socket operatively connected with the upper end of said spindle adapted to receive the base portion of a signal lamp; and signal blades connected with and radiating from said socket, said blades being positioned in the same horizontal plane as the 10 base portion of the lamp positioned in said socket, substantially as described.

3. In a switch target, the combination with the rotary spindle of a switch post, of 15 a socket operatively connected with the upper end of said spindle adapted to receive the base portion of a signal lamp, said socket comprising a base member adapted for operative connection with the upper end of 20 said spindle; outwardly and upwardly projecting arms on said base member; and an annulus constituting the lateral walls of said socket; and signal blades connected with said arms and projecting outwardly 25 therefrom, substantially as described.

4. In a switch target, the combination with the rotary spindle of a switch post, of a socket operatively connected with the up-

per end of said spindle adapted to receive the base portion of a signal lamp, said socket 30 comprising a base member having an opening therein for engagement with the upper end of said spindle; outwardly and upwardly projecting arms on said base member; an integral connection between the upper ends of said arms; and signal blades connected with said arms and projecting outwardly therefrom, substantially as described.

5. In a switch target, the combination with the rotary spindle of a switch post, of 35 a member mounted upon the upper side of said post and operatively connected with the upper end of said spindle; a plurality of signal blades projecting outwardly from said member; and an upwardly opening socket in said member for the reception of the base portion of a signal lamp, substantially as described.

In testimony whereof I have signed my 40 name to this specification in the presence of two subscribing witnesses.

WILLIAM R. RYAN.
